DESIGN FOR A PLUMBING FIXTURE

John Tjaarda, Birmingham, Mich., assignor to Briggs Manufacturing Company, Detroit, Mich.,
a corporation of Michigan

Application April 9, 1934, Serial No. 51,357

Term of patent 14 years

To all whom it may concern:

Be it known that I, JOHN TJAARDA, a subject of the Netherlands, residing at Birmingham, in the county of Oakland, State of Michigan, have invented a new, original, and ornamental Design for a Plumbing Fixture, of which the following is a specification, reference being had therein to the accompanying drawing, forming a part thereof, in which—

The single figure is a perspective view of a plumbing fixture embodying my new design.

I claim:

The ornamental design for a plumbing fixture substantially as shown.

JOHN TJAARDA.
